UNITED STATES PATENT OFFICE

2,509,907

MANUALLY OPERATED PORTABLE WASHER

Robert Whitmour Coulter, Massillon, Ohio, assignor of one-half to George H. Coulter, Massillon, Ohio

Application May 17, 1945, Serial No. 594,207

5 Claims. (Cl. 15—74)

1

This invention relates to washing machines and has more specific reference to a portable type which is suitable and practicable for use in washing dishes, cutlery, and utensils, and the like.

More specifically, the form of the invention representing what is believed to be a preferred embodiment is characterized by a tank suitably constructed to sit in a conventional kitchen sink, said tank being provided with a hinged cover and said cover being adapted to swing over the usual drainboard and when, inverted, serving as a water containing utensil rinsing pan. The tank serves as a receptacle for the washing water and also as a container for a rotary brush assembly such as serves to facilitate and insure the desired results.

One of the objects of the invention is the provision of the lid or cover equipped tank wherein the lid, when it is turned upside-down, serves as a rinsing pan, the latter being provided with an adjustable prop or leg which facilitates placement and retention of said pan in a desirable position to insure convenient and effective results.

Another object has to do with the aforementioned cover equipped cover wherein the tank has an inturned marginal flange which, when said cover is closed, serves to effectively seat itself on the upper edge of the open top of said tank.

Another object and resulting advantage has to do with the bodily insertible and removable dual brush assembly, this characterized by a frame structure to accommodate oppositely rotating brushes, handle means whereby said frame structure may be placed in position and removed in relation to the tank, and crank shaft and gear means suitably and aptly constructed to insure appropriate driving of the brushes and practical mounting of the brush assembly in the tank.

Other features and advantages will become more readily apparent from the following description and the accompanying illustrative drawings.

In the drawings, wherein like numerals are employed to designate like parts throughout the views:

Figure 1 is an elevational view of a so-called portable type dish and utensil washing machine constructed in accordance with the invention, the cover being closed.

Figure 2 is an end elevation of Figure 1 observing the same in a direction from right to left.

Figure 3 is a side elevational view based on Figure 1 and showing how the device is placed in a sink with the rinsing pan resting adjustably on the drainboard.

2

Figure 4 is a top plan view, this on a scale sufficiently enlarged to bring out the gearing and associated parts in details.

Figure 5 is a central vertical sectional view taken on the plane of the line 5—5 of Figure 4, looking in the direction of the arrows.

Figures 6 and 7 are transverse vertical sections on the planes of the lines 6—6 and 7—7 of Figure 5, looking in the direction of the arrows.

10 Referring now to the drawings by the distinguishing reference numerals, it will be seen that the tank, which is of appropriate size and material is denoted by the numeral 10. It is of rectangular box-like form and of suitable depth. 15 The lid or cover is denoted by the numeral 11 and this is hingedly attached to one end wall as at 12. The cover is provided with a marginal in-turned lip or flange 13 which fits tight and effectively on the upper edge of the open top of the tank when the cover is closed, as is obvious. 20 In connection with the cover it is to be repeated that it is employed as a pan to contain water W, this for rinsing purposes. Thus, when the lid is inverted as shown, for instance, in Figure 5, it is desirable to provide an adjustable leg. This comprises a screw 14 having a suitably padded head 15 to rest on the drainboard A, said screw being threaded into a socket 16 secured by an attaching disc 17 to the lid.

25 30 The tank 10 is adapted to sit in the receptacle portion B of the regular sink. The end wall of the tank opposite to the hinge 12 is provided with an adapter notch 18 to accommodate the associated structure on the insertible and removable brush equipped washer unit 19. The unit 19 comprises a substantially U-shaped frame including a bottom or connective web 20 with upstanding end walls 21 and 22. The end walls are braced by suitable reinforcing rods 23 appropriately secured thereto. They are also provided with bearings to accommodate journals on the top portions 24 of the companion brushes 25 and 26.

35 40 These are suitable bristle brushes and the adjacent portions thereof slightly overlap for effective cleansing results. Getting back to the end walls, it will be seen that the wall 21 is provided with an extension 27 having a yoke 28 provided with a handle grip 29 (see Figure 7). The numeral 30 designates suitable reinforcing webs. 45 50 The end wall 22 (see Figure 5) is provided with an extension 31 having a lateral upper free end terminal 32 which extends through and outwardly beyond the adapter notch 18. This extension which serves as a shelf is provided with a bearing 33 to accommodate the crank-shaft 34. A set-screw, which preferably runs in a groove (not

shown) in the crank-shaft, said set-screw being indicated at 35, is carried by the bearing 33. The inner end of the crank-shaft is provided with a beveled gear 36 and meshed with a companion gear 37 on the upper end of a vertical drive shaft 38, the latter mounted for rotation in a bearing 39 on the extension 31. The lower end of the shaft 38 is provided with a beveled gear 40 to transmit motion to the horizontal driven shafts 41 and 42, these mounted for rotation in suitably mounted bearings 43. The adjacent journals on the brushes are provided with beveled pinions 44 and 45 with which complementary beveled gears or pinions 46 and 47 mesh. The arrangement of the gearing is such that the brushes 25 and 26 are turned in opposite directions, that is, directions opposite to each other. It is desirable to accomplish this for it has proven to insure more effective brushing and washing results.

I have shown the structure with the parts closed in Figures 1 and 2. However, in Figures 3 and 5 I have shown the parts in elevation and section to illustrate how the machine is used. As evident, the tank is placed in the receptacle portion 48 of the sink B. The lid is swung to open position and the leg 14 is adjusted so that the rest 15 resides in suitable contact with the drainboard A. The lid then becomes a pan and the pan is filled with hot water for rinsing purposes. The main tank 10 is also filled and, assuming the brush assembly is therein, the structure is ready for use. By turning the crank-shaft, the shafts and gearing serve to rotate the brushes in opposite directions and by holding the dishes and utensils in contact with the brushes, grease and deposits are readily removed and the articles are then ready for rinsing, this in an obvious manner.

The tank and lid can be placed under the hot water spigot and washed, cleaned and dried ready for next use. The entire brush means can be lifted out from the tank and it too can be washed and reconditioned for subsequent use.

It will be noted that the extension 32 serves not only as a shelf to support a part of the gearing and crankshaft arrangement, but it also functions as a handle and is seated in the keeper notch 18. That is to say, it functions as a handle in conjunction with the hand grip 29. This facilitates inserting and removing the entire brush-unit.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a portable dish and utensil washer of the class described, a rectangular box-like casting comprising an open top tank provided with closure means, a bodily insertable and removable U-shaped frame telescopically arranged on the interior of said tank, said frame including parallel vertical end members, said end members having extensions at their upper ends, one of said extensions being provided with a hand-grip, the opposite extension being directed outwardly and laterally to assume a horizontal po-

sition, the adjacent vertical wall of said tank having a notch through and beyond which said last-mentioned extension projects, brushes mounted for rotation in said frame, a crank shaft 5 mounted in a bearing carried by said last-mentioned extension, a plurality of shafts and gears interconnected in operating relation, carried by said U-shaped frame and serving to transmit the motion from the rotatable crank shaft 10 to the rotatable brushes in a manner to rotate said brushes in directions opposite to each other.

2. A portable dish and utensil washer of the class described comprising a relatively deep flat bottomed tank shaped and proportioned to sit firmly in the customary receptacle portion of a standard-type kitchen sink, said tank being of such vertical height that the upper open end thereof extends well above the plane of the sink receptacle portion and the usual complementary drain-board, and a cover hinged to the upper open end portion of said tank, said cover embodying a lid portion and bordering vertical rim-forming walls and being shallow in comparison to the depth of said tank and, when swung over 15 the drain-board and inverted serving as a pan for water used in rinsing dishes and utensils, the vertical rim-walls of said cover being marginally provided with a horizontal in-turned anti-splash flange adapted to rest on the upper open 20 edge portion of the tank when the cover is closed over said tank, a single adjustable leg mounted centrally on the lid portion of said cover, said leg having a head adapted to rest in contact with a drain-board in a manner to regulate the position and level of the cover when the latter is 25 swung open and used as the aforementioned rinsing pan.

3. The structure specified in claim 2, said adjustable leg being in the form of a headed set-screw, and a screw threaded socket mounted on 30 said lid portion, said set-screw being threaded into said socket.

4. In a portable dish and utensil washer of the class described, an open top tank provided 45 with closure means, a bodily insertable and removable U-shaped frame fitted telescopically and snugly on the interior of said tank, said U-shaped frame including vertical end members, said end members being provided on their respective upper end portions with extensions, one of said 50 extensions being provided with a hand-grip, the opposite and remaining extension having an outwardly and laterally directed terminal portion disposed in a horizontal plane, the coacting and projecting wall of said tank being formed with 55 a notch and said laterally directed portion of the extension being fitted in and extending outwardly beyond said notch and the adjacent wall of said tank, brushes rotatably mounted for operation of said U-shaped frame, and means on 60 said frame connected with said brushes for mechanically driving the brushes.

5. A portable dish and utensil washer of the class described comprising a relatively deep flat bottomed tank shaped and proportioned to sit firmly in the usual receptacle portion of a standard-type kitchen sink having a drain board, said tank being of such vertical height that the upper open end thereof extends well above the 65 plane of the sink receptacle portion and the complementary drain-board, and a cover hinged to the upper open end portion of said tank, said cover being shallow in comparison to the depth of said tank and, when swung over the drain-board and inverted, serving as a pan for water 70

used in rinsing dishes and utensils, the rim-walls of said cover being marginally provided with a horizontal inturned anti-splash flange adapted to rest on the upper open edge portion of the tank when the cover is closed over said tank, a bodily insertable removable U-shaped frame fitted telescopically in said tank and enclosed by said cover when the latter is closed, said frame including parallel vertical end members, said end members having extensions at their upper ends, one of said extensions being provided with a hand grip, the opposite extension being directed outwardly and laterally to assume a horizontal position, the wall of said tank adjacent said last-mentioned extension having a notch through and beyond which the extension projects, brushes mounted for rotation in said frame and confined within the limits of said tank, a crank-shaft

mounted in a bearing carried by said last-mentioned extension, and an operating connection between the crank-shaft and brushes.

ROBERT WHITMOUR COULTER.
